No. 761,356.

PATENTED MAY 31, 1904.

W. H. BURRITT.
APPARATUS FOR LASTING SHOE UPPERS.

APPLICATION FILED MAY 25, 1903.

NO MODEL.

UNITED STATES PATENT OFFICE.

WILLIAM H. BURRITT, OF ST. LOUIS, MISSOURI.

APPARATUS FOR LASTING SHOE-UPPERS.

SPECIFICATION forming part of Letters Patent No. 761,356, dated May 31, 1904.

Application filed May 25, 1903. Serial No. 158,754. (No model.)

To all whom it may concern:

Be it known that I, WILLIAM H. BURRITT, a citizen of the United States, residing at St. Louis, State of Missouri, have invented certain new and useful Improvements in Apparatus for Lasting Shoe-Uppers, of which the following is a full, clear, and exact description, reference being had to the accompanying drawings, forming a part hereof.

10. My invention has relation to improvements in apparatus for forming rubber shoe-uppers; and it consists in the novel arrangement and combination of parts more fully set forth in the specification, and pointed out in the claims.

15. In the drawings, Figure 1 is a top plan of the apparatus. Fig. 2 is a rear elevation thereof. Fig. 3 is a side elevation thereof. Fig. 4 is a front elevation showing the bag or inflatable diaphragm partly inflated. Fig. 5 is a cross-section on line 5-5 of Fig. 3, showing the device fully inflated; and Fig. 6 is a perspective showing a conventional form of a rubber shoe-upper.

The object of the present invention is the 25 construction of an apparatus which will apply the outer rubber layer to a shoe-upper, dispensing in a great measure with hand labor, and at the same time insuring uniform results. Under the prevailing method of construction of rubber uppers the lining or stockinet and the insole is first mounted on a suitable last supported right side up, the blank forming the outer rubber layer being deftly passed by hand over the stockinet, beginning at a point approximately at the middle of the upper, then passing it forward and along the sides, and then rearward. It is apparent, however, that with the hands it is next to impossible to cause this layer to adhere uniformly throughout its entire area, and the final result is that at points air will 35 find a lodging-place between the rubber layer and stockinet, which must eventually be expelled by a roller passed over the completed upper, an operation requiring considerable time, and thus increasing the cost of manufacture.

50. My present apparatus contemplates a method of applying the rubber layer by pneumatic or equivalent pressure, the rubber

blank being caused to progressively adhere to the stockinet or lining under the action of an inflatable bag or diaphragm, which in the process of inflation gradually envelops the last and stockinet mounted on it, such gradual 55 envelopment forcing the rubber layer against the last and causing the same to adhere to the stockinet, all as will more fully appear from a detailed description of the invention, which is as follows:

Referring to the drawings, 1 represents a suitable block or supporting member adapted to be secured to a table or any convenient support, (not shown,) the sides of the block having secured thereto the rearwardly-projecting strips 2, between whose free ends is adapted to be received the last-supporting arm 3, held in position by a transverse bolt 4 and tightening-nut 5. The bolt 4 passes through the right-angularly-disposed slots 6, 7, formed, respectively, in the arms 3 and 2, said slots permitting both of a vertical and backward and forward adjustment of the arm, as is obvious, (see dotted position of the parts in Fig. 3) to accommodate lasts of different 75 sizes. The upper end of the arm 3 has a forwardly-inclined surface for supporting the last L, (L'), the latter being held thereon by the pins 8, entering corresponding sockets formed in the top of the last, the forward end of the last 80 being additionally secured by the clamping-arm 9, pivoted to the front end of the member 1. The arm is drawn toward the last by a spring 10, attached, respectively, to the arm above its pivotal point and to the member 1, so that the 85 arm may be disengaged from the last when desired, (see dotted position, Fig. 3,) the line of draft of the spring under those circumstances passing through the pivot of the arm. The free end of the arm is provided with a 90 pivoted plate 9', bearing directly upon the bottom of the last, the pivotal connection thereof permitting it to conform to any shape or angular disposition of the last.

Hinged along the upper edge of the member 1 on each side are leaves 11, the adjacent sides of which in the rear extend slightly beyond the rear ends of the strips 2, so as to fully encompass a last L' of maximum dimensions. The leaves 11 jointly form the back- 100

ing or support for a suitable inflatable bag or diaphragm 12, preferably made of elastic material, such as vulcanized rubber, (though other suitable material, such as silk and the like, 5 might answer,) the lower wall of the bag covering the leaves and spanning the member 1 for the full length thereof, Figs. 1, 4, 5. The outer edges of both walls of the bag are folded over the edges of the leaves, Figs. 4, 10 5, and cemented thereto and to one another and additionally secured to the leaves by pegs 13. Disposed along the rear edge of one of the leaves is an air-induction or feed valve 14 and a vent-valve 15, the former being carried by a pipe 16, disposed along the bottom of the leaf and entering the bag at one point, and the latter being carried by a shorter pipe 17, entering the bag rearward of the pipe 16. These valves are ordinary two-way cocks, 15 well known and requiring no detailed description. The valve 14 controls the admission of compressed air conveyed from any suitable source of supply (not shown) through a flexible hose 18, and the valve 15 allows for the 20 escape of such air from the bag at the proper moment.

Laid upon the diaphragm 12 in a position shown in Fig. 1 is the rubber blank which is to constitute the outer layer of the shoe-upper, this blank for a conventional form of shoe, Fig. 6, being composed of a forward portion *a*, the lateral wings *b b*, and a central lobe or tongue *c*. The last L has first passed over it the stockinet *s*, the insole *i*, and the 30 marginal "piping" *p*, over which the rubber blank is to be folded in the formation of the completed upper.

The operation of the device may be described as follows: Let us assume that the parts are 40 disposed as seen in Figs. 1, 2, 3. The operator closes valve 15 and opens valve 14, permitting compressed air to inflate the bag or diaphragm 12, the first effect of the inflation being to cause the bag to bulge at the center and contact with the last at approximately the point *x* (indicated in Fig. 3)—that is to say, slightly in advance of the instep of the shoe, Fig. 4. The inflated diaphragm will thus carry the rubber blank with it, causing the latter with further inflation to progressively contact with the last, first along the front of the last, then along the sides, Fig. 5, and eventually along the rear until every portion of the last is enveloped by the rubber blank. The only hand-work to be performed is in bringing together the ends of the wings *b b*, which form the rear seam of the shoe. These are brought together by slightly overlapping one end over the other and trimming off the excess. So, also, are the 50 overlapping edges *e* of the blank, Fig. 5, trimmed properly before pasting on the outer sole. (Not shown.) The progressive inflation of the bag or diaphragm causes the leaves to close or fold, as seen in Figs. 4 and 5, this 55 closing resulting from the tension exerted on

the upper wall of the diaphragm as a result of the inflation. The greater the inflation the greater will be the tendency of the leaves to close, and when the bag is inflated to the full extent the leaves will rise sufficiently to 70 cause the upper wall of the bag to snugly envelop the last, and thus attach the rubber blank. The latter, it must be understood, is made of rubber, and before it is vulcanized it adheres on the slightest contact; but since with my 75 present improvement the succession of the surfaces of contact is from the center outward and rearward and gradually progressive in the directions indicated it is apparent that when the shoe is completed an eminently successful 80 result is attained, a result which it is impossible to secure by applying the rubber layer by hand. Of course the bag being made of vulcanized rubber does not adhere to the rubber blank, so there is no danger of the blank 85 sticking to the bag.

It will be seen that in the present case the last is held in an inverted position. The object of this arrangement is to prevent the "upper" blank from adhering thereto except 90 as it may be forced against it by the gradually-inflating surface of the bag. Normally the blank tends to drop away from the last under the action of gravity, so there is not the danger of the blank adhering to the last except 95 as it may be forced upward against it. By the old hand method, where the last was mounted right side up, the operator was under great disadvantage by reason of the blank dropping toward and against the last and adhering to 100 the stockinet covering thereof at points which were not desired and from which it could not advantageously be disengaged after it once adhered, for it must be remembered that the rubber while being applied sticks with the 105 slightest contact.

While I preferably employ compressed air as the inflating medium, I may of course use water, gas, or any available fluid. Once the bag is fully inflated the cock 14 is shut off until the operation is complete, when the vent-valve 15 is opened, thus allowing the air to escape, whereupon the leaves drop and the bag collapses to its normal position for the next operation. The upper blanks are kept separated by oiled leaves, so as to prevent adhering to one another, and as one shoe is completed the next blank is placed on the diaphragm in readiness for the next operation. 110 115

I do not wish, of course, to be limited to 120 the details here shown, as they may be considerably departed from without an actual departure from the nature or spirit of my invention.

Having described my invention, what I 125 claim is—

1. In an apparatus for lasting shoe-uppers, a suitable inflatable diaphragm, hinged leaves to which said diaphragm is secured, a suitable support for said leaves, and means for in- 130

- flating said diaphragm, substantially as set forth.
2. In an apparatus for lasting shoe-uppers, a suitable inflatable diaphragm, hinged leaves to which said diaphragm is secured, a suitable support for the leaves, and means for supporting a last within the angle of the sweep of the leaves, substantially as set forth.
3. In an apparatus for lasting shoe-uppers, a suitable inflatable diaphragm, hinged leaves to which said diaphragm is secured, means for supporting a last between the hinge-axes of the leaves, and means for inflating the diaphragm, the leaves gradually folding under the progressive inflation and causing the inflated surface of the diaphragm to progressively engage and envelop the contour of the last, substantially as set forth.
4. In an apparatus for lasting shoe-uppers, a suitable inflatable diaphragm, hinged leaves to which said diaphragm is secured, means for supporting a last in an inverted position above the diaphragm and between the hinge-axes of the leaves, and means for inflating the diaphragm, the leaves gradually folding under the progressive inflation of the diaphragm and causing the inflated surface of the latter to progressively engage and envelop the contour of the last, substantially as set forth.
5. In an apparatus for lasting shoe-uppers, a suitable inflatable diaphragm, hinged leaves to which said diaphragm is secured, means for adjustably supporting a last in an inverted position over the diaphragm and between the hinge-axes of the leaves, and means for inflating the diaphragm, the leaves gradually folding under the progressive inflation of the

diaphragm and causing the inflated surface of the latter to progressively engage and envelop the contour of the last, substantially as set forth.

6. An apparatus for lasting shoe-uppers comprising a pair of leaves hinged to a common support, an inflatable diaphragm secured to said leaves, means for adjustably supporting a last in an inverted position over the diaphragm, a clamping-arm hinged to said support and adapted to be swung into engagement with the bottom of the last, an induction-valve and a vent-valve carried by one of the leaves of the diaphragm, and pipes leading from said valves to the interior of the diaphragm, substantially as set forth.

7. An apparatus for lasting shoe-uppers comprising a supporting member, rearwardly-projecting strips disposed on either side thereof, a last-supporting arm having intersecting slots, located between the projecting ends of the strips, a bolt passed through the strips and through the slots of the said arm, a tightening-nut for said bolt, leaves hinged to the supporting member above the strips, an inflatable bag or diaphragm carried by said leaves, feed and vent valves for said diaphragm, and a spring-controlled pivoted arm for clamping the last, carried by the supporting member, the parts operating substantially as and for the purpose set forth.

In testimony whereof I affix my signature in presence of two witnesses.

WILLIAM H. BURRITT.
